WITNESS:

UNITED STATES PATENT OFFICE

CHARLES L. MORGAN, OF PITTSBURGH, PENNSYLVANIA

DETACHABLE SASH

Application filed December 28, 1927. Serial No. 243,192.

This invention relates to means for hanging sliding window sash and like slidingly mounted members, whereby the sash may be opened and closed in the ordinary manner, or swung laterally for the purpose of conveniently washing the window panes or for other purposes.

Another object of the invention is the provision of a weight balanced sash having novel means for attaching the sash cord or chain thereto so that the cord may be detached to release the sash, together with means for holding the cord against movement with respect to the window frame, whereby the cord will be retained in position to be again conveniently attached to the sash.

With the above and other objects in view, the invention further includes the following novel features and details of construction to be hereinafter more fully described, illustrated in the accompanying drawings and pointed out in the appended claims.

In the drawings:—

Figure 1 is an elevation showing a portion of a window with the invention applied.

Figure 2 is an enlarged fragmentary vertical section illustrating the means of attaching the sash cord to the sash with the parts in locked position.

Figure 3 is a view similar to Figure 2 showing the parts in released position.

Figure 4 is an enlarged fragmentary sectional view taken on the line 4—4 of Figure 1.

Figure 5 is a similar view showing the sash hingedly supported and swung to an open position.

Figure 6 is a face view of a portion of a window frame showing the cord carried section of the attaching member.

Referring to the drawings in detail where-in like characters of reference denote corresponding parts, the reference character 10 indicates a window sash which is slidingly mounted in a frame 11. One side of this frame is provided with a longitudinally extending groove 12, but the adjacent edge of the sash 10 does not enter this groove and the usual retaining and guide strips at this side of the frame may or may not be dispensed with. The sash however is of the

slidely mounted weight balanced type and for this purpose has attached thereto one end of a cord or chain 13, the attaching means which forms a part of the present invention being of a character to permit of the cord being readily attached to or detached from the sash. For this purpose there is provided a sectional cord attaching member which comprises a section 14 and a section 15. The section 14 is slidable in the groove 12 of the window frame, while the section 15 is positioned within a groove 16 provided in the adjacent stile of the sash 10. The groove 16 may or may not be, but preferably is provided with a metal lining 17 within which the section 15 has a sliding fit. A small section of the sash is left in the groove 12 to provide a seal.

The section 15 is provided with spaced parallel inclined slots 18 which receive pins 19 extending transversely of the groove 16, so that the section 15 may have a lateral sliding movement within the groove 16 and will be moved vertically during such sliding movement. Guide pins 20 have their inner ends secured to the sash 10 and are received within parallel inclined openings 21 provided in the section 15. The section 15 further includes a transversely U-shaped metallic member 22 within which is secured a block 23. This block is shaped as shown in Figures 2 and 3 of the drawings so that the side walls of the member 22 extend beyond the outer longitudinal edge of the block for the major portion of their length, as indicated at 24. When the sections 14 and 15 are connected in a manner to be explained, these extended portions 24 of the side walls will enter the groove 12 upon opposite sides of the section 14.

The section 14 comprises a hollow transversely rectangular casing which is provided with an opening 25. Extending across this opening is a pin 26 which is adapted to be engaged by a tongue 27 which extends from the adjacent face of the section 15. By reference to Figure 3 of the drawings, it will be seen that when the section 15 is moved outwardly and downwardly, the tongue 27 will occupy a position above the pin 26. When

the sash is raised, the weight (not shown) upon the opposite end of the sash cord 13, will move the section 14 upwardly in accordance with the movement of the sash 10 so as to balance the sash. When the sash 10 is moved downward, engagement of the tongue 27 with the pin 26 will bring the section 14 and the adjacent portion of the sash cord 13 downward, as will be readily understood.

5 The purpose of the invention is to release the sash from the cord so that the sash may be swung inward, and in order to permit of this inward swinging movement, the opposite edge of the sash 10 may be hingedly or otherwise mounted. Various means may be devised for this purpose, but it is preferred to employ the means shown and described in my copending application. This means consists of a hinge which embodies a stationary hinge plate 27. This plate is preferably mortised within the window frame within a groove defined by strips 28 and 29. The strip 29 is cut away to receive spaced lugs 30 which are carried by the plate 27 and this plate is provided with an opening 31. The opening 31 accommodates a plate 32 which is hingedly secured to the plate 27 by means of a link 33 whose opposite ends receive pins 34 which extend through the lugs 30 of the plate 27, and through lugs 35 which extend from the plate 32. The lugs 34 are also received within the cut-away portion of the strip 29.

10 The outer end of the plate 32 is provided with a flange 36 within which is provided a groove 37 and this groove slidably receives one edge of a plate 38 which is secured to the adjacent face of the sash 10. The opposite edge of this plate engages within grooves 39 provided in the lugs 35, so that the plate 38 is slidably mounted with respect to the hinge plate 32. When the parts are in the position shown in Figure 4 of the drawings, the sash may be raised and lowered in the ordinary manner.

15 The plate 38 carries a sleeve 40 which may or may not be integral with the plate and which accommodates a locking bolt 41 and this bolt is provided with a finger piece 42 which extends through a slot 43 provided in 20 the sash. The bolt 41 is adapted to enter an opening 44 provided in the plate 32, and when the bolt is engaged within this opening, the sash 10 will be locked to the hinge plate 32.

25 Normally, the parts are arranged as shown in Figure 4 of the drawings with the bolt 41 disengaged from the plate 32, so that the sash 10 may be raised or lowered. When it is desired to swing the sash laterally upon the 30 hinges, the finger pieces 42 of each hinge are slid inward or toward the adjacent portion of the window frame, so that the bolt 41 will enter the opening 44. The sash cord attaching member is then operated to move 35 the section 15 from the position shown in

Figure 2 to the position shown in Figure 3, so that this edge of the sash will be released and the sash may be swung to the position shown in Figure 5.

30 In order to manipulate the section 15 of the cord attaching member, the lining 17 of the groove 16 has extending therefrom spaced apertured ears 45. Pivotally mounted between these ears upon a pivot pin 46 is a lever 47. This lever includes a finger piece 48 and arm 49 which engages between spaced projections 50 provided in the upper end of the section 15. By swinging the finger piece 47 upward to the position shown in Figure 3 of the drawings, the section 15 will be moved inward and upward so as to disengage the tongue 27 from the pin 26. The section 15 is then free from the section 14 so that these sections may be moved independently of one another.

35 In order to prevent the weight from drawing the sash cord 13 upward, the section 14 has pivotally mounted therein a dog 51. This dog has one of its ends forced through an opening 52 provided in the casing of the section 14 so that it may enter an opening 53 provided in a plate 54 which is secured within the bottom of the slot 12 of the window frame. A spring 55 is utilized for forcing the dog through these openings, this spring engaging the lower end of the dog so that as soon as the opening 51 registers with the opening 52, the dog will be forced inward. The opposite end of the dog however is arranged in the path of the tongue 27, so that when the parts are in the locked position shown in Figure 2, the dog 51 will be prevented from entering the opening 52 and the section 14 which is attached to the cord 13 may have free sliding movement within the slot 12. Before manipulating the finger piece 47 to release the cord, the sash is moved into position so as to permit the dog to enter the opening 52, so that when the sections are released, the spring 55 will force the dog into the opening 52 and prevent the sash cord from moving upward under the influence of the sash weight. When the parts are in proper position to lock the sash to the hinges, the dog will be in proper position to enter the opening 52.

40 The lever 47 carries laterally spaced extensions 56 of a length to engage the frame 11 upon opposite sides of the slot 12, and this frame 11 is recessed upon each side of the slot as shown at 57. The recesses 57 are so located as to permit the lever 47 to be operated to move the section 15 only when the section 14 is in proper position to be locked to the frame 11.

45 The invention is susceptible of various changes in its form, proportions and minor details of construction and the right is herein reserved to make such changes as properly fall within the scope of the appended claims.

Having described the invention what is claimed is:—

1. The combination with a window frame and a slidably mounted sash, of a sectional cord attaching member, means to secure a sash cord to one section of said member, means to secure the other section of said member to the sash, means to lock the sections together to connect the cord and sash, and means to release said sections to release the cord from the sash. 70
2. The combination with a window frame and a slidably mounted sash, of a sectional cord attaching member, means to secure a sash cord to one section of said member, means to secure the other section of said member to the sash, means to lock the sections together to connect the cord and sash, means to release said sections to release the cord from the sash, 75
- 20 spring actuated means to lock the cord carried section to the window frame when the cord is released from the sash, and means to release the locking means when the sections are connected. 80
- 25 3. The combination with a window frame and a slidably mounted sash, of a sectional cord attaching member, means to secure a sash cord to one section of said member, means to secure the other section to the sash to permit of lateral movement of said section, means to move the sash carried section laterally, means to lock the sections together when the sash carried section is moved in one direction and to release the sections when said 85 sash carried section is moved in an opposite direction, means to lock the cord attached section to the window frame when the sections are separated and means to release the said cord attached section from said frame when the sections are connected. 90
- 40 4. In combination with a window frame having a groove therein and a sash slidably mounted in the frame and having a groove opposed to the groove of said frame, a cord attaching member located within the groove of the sash and frame and comprising a cord carried section located and slidable within the groove of the frame and a sash carried section located within the groove of the sash, means 95
- 45 to secure the cord carried section to the sash cord, means to secure the sash carried section to the sash to permit of lateral sliding movement of said section, means to provide an interlocking connection between said sections 100
- 50 when the sash carried section is moved in one direction and to release said connection when the section is moved in an opposite direction and means to move said section. 105
- 55 5. The combination with a window frame having a groove therein and a sash slidably mounted in the frame and having a groove opposed to the groove of said frame, a cord attaching member located within the groove of the sash and frame and comprising a cord 110
- 60 carried section located and slidable within 115
- 65 the groove of the frame and a sash carried section located within the groove of the sash, means to secure the cord carried section to the sash cord, means to secure the sash carried section to the sash to permit of lateral sliding movement of said section, means to provide an interlocking connection between said sections 120
- 70 when the sash carried section is moved in one direction and to release said connection when the section is moved in an opposite direction and means to move said section. 125
- 75 6. The combination with a window frame having a groove therein and a sash slidably mounted in the frame and having a groove opposed to the groove of said frame, a cord attaching member located within the groove of the sash and frame and comprising a cord carried section located and slidable within 130
